UNITED STATES PATENT OFFICE.

WILLIAM E. NEWMAN AND DAVID K. STUART, OF OGDEN, UTAH.

FLUME.

1,353,264.

Specification of Letters Patent. Patented Sept. 21, 1920.

Application filed June 22, 1920. Serial No. 390,879.

To all whom it may concern:

Be it known that we, WILLIAM E. NEWMAN and DAVID K. STUART, citizens of the United States, residing at Ogden, in the county of Weber and State of Utah, have invented a new and useful Flume, of which the following is a specification.

This invention relates to sectional metallic flumes, and more particularly to the junction between the various sections whereby a tight joint will be effected, which will at the same time allow for considerable expansion or contraction, due to large changes in temperature.

15 A further object is to provide a metallic flume in which the various sections are so jointed as to form a substantially continuous surface and thus minimize the friction of the liquid against the sides of the flume.

20 Another object is to provide a flume with outstanding longitudinally extending flanges, allowing the flume to be conveniently supported and adding materially to the strength and rigidity of the same.

25 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

35 In the drawings accompanying this specification and forming a part thereof, the preferred embodiment of our invention is illustrated, in which:—

40 Figure 1 is a top plan view of a portion of a flume embodying our invention.

Fig. 2 is a cross sectional view taken on the line 2—2 of Fig. 1.

Fig. 3 is a view in perspective of the upstream end of a flume section.

Fig. 4 is a view in perspective of the downstream end of the adjoining or continuous section.

Fig. 5 is a sectional view taken on the line 5—5 of Fig. 1.

Referring to the drawings in which similar reference numerals designate corresponding parts throughout the several views, the flume is composed of a plurality of sections, 55 each of which is provided with two dissimilar ends, arbitrarily spoken of as the up-

stream or secondary end U and the downstream or primary end D. The upstream end of one section cooperates with the downstream end of the adjacent section to effect 60 a tight and at the same time expansible junction therebetween.

The end U is formed by cutting the side flanges 5 away from the extreme end of the section and slightly beveling the upper ends 65 of the section as at 6. In this connection, it is to be noted that the flume sections may be other than semi-cylindrical, if it be so desired. The side flanges 5 which outstand from the upper edges of the flume sections 70 are designed to support the sections and to add considerable rigidity thereto.

The downstream end D of the adjacent flume section is formed by cutting back the flange 5' away from the section end. The 75 end is then folded rearwardly upon itself to form the annular and connected plate 7, the extremity of which is then folded forwardly to form the outer annular and connected plate 8. The spaced but connected 80 annular plates 7 and 8 define a socket 9 therebetween which is open or exposed so as to receive the upstream end U of the adjacent section therein. The outermost fold or annular plate 8 extends a distance be- 85 yond the extremity of the fold 7, as illustrated in Fig. 4. This provided for the quick and easy assembling of the flume sections and also presents a large bearing surface or area between the meeting and interengaging ends of the sections. The flanges 5 and 5' are provided with the notched portions 10 which coact to define a bolt-receiving opening therebetween.

A metallic rod 11 extends around the 95 outer fold or plate 8 and is provided with the tightening nuts 12 on the extremities thereof which engage the cross bar 13, or brace and are adapted to draw the rod 11 into rigid and forced contact with the outer 100 fold 8, thus compressing the same against the upstream end of the adjacent section which is interposed between the folds or annular plates 7 and 8. The binder or securing rod 11 extends between the notches 105 of the flanges 5 and 5' of the flume sections and thus does not interfere with the flanges. A rigid and tight juncture will thus be obtained between the meeting ends of the flume sections and said juncture will present 110 substantially a continuous surface. The flume is to be so positioned that the direc-

tion of flow of the liquid will be from upstream to the downstream end of each section. The wide bearing surface obtained between the two sections provides for the liquid-tight juncture therebetween, and which is not in any way destroyed by the expansion or contraction of the sections which may take place within the recess 9.

It is to be observed that the flanges 5' on the downstream or primary section overhang the sockets 9. Because the upper edges of the secondary or upstream section are beveled as shown at 6 in Fig. 3, the protruding end of the upstream or primary section may pass readily beneath the flanges 5'. The notches 10 in the flanges 5 and 5' cooperate to form at the ends of the flanges of the respective sections, fingers 50 which overlap the outer edge of the binder 11. These fingers 50 not only aid in holding the binder in its arched form, but, as well, serve as supports for the ends of the brace 13.

Having thus described the invention, what is claimed is:

A flume comprising trough-shaped primary and secondary sections provided along their edges with lateral flanges, the primary section being folded rearwardly and forwardly upon itself to form an exterior transverse socket across the upper edges of

which the flanges of the primary section extend, the extremity of the secondary section being inserted into the socket, and the upper edges of the secondary section being beveled to permit the same to pass beneath the flanges of the primary section, the flanges of both sections being set back from the ends of the respective sections to permit the beveled extremity of the secondary section to enter the socket; a brace extended transversely of the sections; and a binder uniting the ends of the brace, the flanges of the sections being cut away close to the body portions of the sections to define openings which receive the binder, and to define at the ends of the flanges of the sections, abutting fingers which overlap the outer edge of the binder and serve at once as supports for the ends of the brace and to prevent an undue telescoping of the sections and a subsequent closing of the openings.

In testimony that we claim the foregoing as our own, we have hereto affixed our signatures in the presence of two witnesses.

WM. E. NEWMAN,
DAVID K. STUART.
